UNITED STATES PATENT OFFICE.

HENRY KOCOUREK, OF CHICAGO, ILLINOIS.

SECURING DEVICE FOR DETACHABLE BUTTONS.

1,376,817.

Specification of Letters Patent.

Patented May 3, 1921.

Application filed April 25, 1919, Serial No. 292,606. Renewed March 23, 1921. Serial No. 454,900.

To all whom it may concern:

Be it known that I, HENRY KOCOUREK, a citizen of the United States, residing at Chicago, in the county of Cook and State 5 of Illinois, have invented certain new and useful Improvements in Securing Devices for Detachable Buttons, of which the following is a specification, reference being had to the accompanying drawings, forming 10 a part thereof.

The purpose of this invention is to provide a means for securing to a fabric or garment, a button of the type having projecting from the back an attaching loop or eye. It consists 15 in the elements and features of construction shown and described, as indicated in the claims.

In the drawings:

Figure 1 is a front view of two parts of 20 a garment secured together by a button embodying this invention.

Fig. 2 is a rear or inside view of the same.

Fig. 3 is an edge view of the button and the securing device, the latter being partly 25 in axial section.

Fig. 4 is an edge view of the button at a position ninety degrees turned from that in Fig. 3, with the attaching device portion of the button in axial section.

Fig. 5 is a section at the line, 5—5, on 30 Fig. 4.

Fig. 6 consists of details of the several parts of the attaching device.

Fig. 7 is a plan view of the outer fabric- 35 clenching washer.

Fig. 8 is a similar view of the inner washer.

Fig. 9 is a section at the line, 9—9, on 40 Fig. 6.

Fig. 10 is a plan view of a blank from which the part, 5 is made by folding.

The particular purpose of this invention is to provide means for attaching a button of the character commonly employed on 45 military and other uniforms, and having a rigid loop or eye projecting from the back for attaching it, in such manner that it shall at all times be held without dangling,— that is, erect from the fabric and thereby 50 neat in appearance,—and adapted to be readily engaged with the button-hole. In the drawings, 1 represents such a button of which 2 is the back disk or plate and 3 the attaching eye. The securing device 55 comprises a flat tubular member, 5, which may be made by folding up a sheet metal blank of

which the ends make a butt-joint as shown at 5^a, (but it is not necessarily formed in this way), the middle portion of the width of the tube being cut away at one end so as to 60 leave standing, projecting from the two narrower sides which are not cut away, tangs, 4, 4, which are preferably sharpened at the ends as indicated at 4^a, to adapt them to penetrate the fabric to which the button is to be attached. In the sharpened ends of each of these tangs there is formed a small eyelet, 14, for engaging a securing device hereinafter described. At the other end the tube is 65 adapted to receive the eye, 3, of the button 70 thrust thereinto, as seen most clearly in Fig. 4, the end of the tube abutting snugly against the back of the button when the eye is thrust into the tube, and the tube being designed to be secured to the button by sinking 75 one side of the tube into the eye of the button as shown at 6 in Fig. 3, but not excluding other means of effecting the securement. For securing the device to the fabric, the tangs, 4, 4, are thrust through the fabric, 80 requiring no other means than their sharpened ends for penetrating it, though the fabric may be pierced with a knife for that purpose if preferred. A washer, 7, however, is first passed onto the tangs, 4, of the tube, 85 said tangs being thrust through apertures, 8, 8, in the washer, and the washer having preferably an additional aperture, 9, to accommodate the end of the eye, 3, so that when the washer is snugly up against the 90 bottom of the shoulder formed at 10 by the recess or notch, cut in the device to form the tangs, 4, the back of the button shall be spaced away from the washer and from the fabric, in which the washer will 95 be embedded, no greater distance than the length of the uncut away portion of the tube which is of course made only sufficient to conveniently accommodate the fabric of the garment which is to be engaged by the button. The device having been thrust into the fabric as described with the washer, 7, in place on the forward or outer side of the fabric, facing the back of the button, a second washer, 11, having apertures, 12, for 100 receiving the ends of the tangs, 4, is applied upon said tangs and pressed closely against the back side of the fabric, and the catch or snap device, 13, which is formed of wire bent in the form of a letter S, with the ends 105 turned outward so as to project directly oppositely away from each other, is then 110

snapped into engagement of its ends with the eyelets, 14, in the ends of the tangs which have pierced the cloth and stand projecting from the back or inner side thereof. The 5 button is now secured in place on the garment, but the projecting tangs, 4, as well as the projecting ends of the snap catch device, 13, would be objectionable, and must be covered to protect interior garments from 10 wear or from injury by reason of these sharp or projecting ends. For that purpose there is provided a cap, 15, which is a disk having a marginal lip, 16, which is re-curved inwardly as shown at 16°, so as to form an 15 inwardly-facing channel. This cap is now snapped over the projecting ends of the tangs, 4, and its re-curved edge, 16°, is snapped into engagement with the ends of the snap spring or catch device, 13, which 20 serve to retain the cap in place while the cap guards and covers said ends.

While this button is entirely secure in its engagement with the fabric, it is readily detachable by springing off the cap, 15, whereupon the snap spring catch, 13, may be disengaged, leaving the tangs free to be withdrawn from the fabric.

I claim:—

1. A button securing device consisting of 30 a flat tube having at one end tangs projecting endwise for penetrating the fabric to which the button is to be attached, and dimensioned at the other end to receive the attaching loop or eye of a button, and to have 35 one or more of its sides engaged therewith, and means for engaging the tangs on the opposite side of the fabric from the button.

2. In the structure defined in claim 1, the tube being engaged with the button loop or

eye by sinking one side of the tube into said 40 eye.

3. In the structure defined in claim 1, the means for engaging the tangs on the opposite side of the fabric, being a spring-wire clip, the tangs having each an aperture for 45 engaging the ends of the clip, and the clip being flexed between its ends to react for thrusting said ends oppositely into said apertures of the tang.

4. In the structure defined in claim 1, the 50 means for engaging the tangs on the opposite side of the fabric from the button, consisting of a spring-wire clip, the tangs having apertures or eyelets for receiving the 55 ends of the clip, and the clip being flexed between its ends for thrusting said ends oppositely into said eyelets of the tangs, and a cap having a marginal lip reflexed inward for encompassing the tangs and the ends of the clip in the inwardly facing groove formed 60 by said reflexed lip.

5. In the construction defined in claim 1, a forward side fabric-clamping washer, apertured for the tangs and adapted to be stopped against the end of the tube between 65 the tangs, and a rear side fabric-clamping washer apertured for the tangs.

6. In the construction defined in claim 1, a forward side fabric-clamping washer apertured for the tangs and adapted to be 70 stopped against the end of the tube between the tangs, and having a central aperture for the button eye or loop and a rear side fabric-clamping washer apertured for the tangs.

In testimony whereof, I have hereunto set 75 my hand at Chicago, Illinois, this 19 day of April, 1919.

HENRY KOCOUREK.
